(57) **CLAIM**

The ornamental design for a swingarm suspension plate, as shown and described.

DESCRIPTION

FIG. 1 is a front view of a swingarm suspension plate showing our new design. A rear view is a mirror image thereof.

FIG. 2 is a left-side view thereof.

FIG. 3 is a right-side view thereof.

FIG. 4 is a bottom view thereof.

FIG. 5 is a top view thereof.

FIG. 6 is a left front perspective view thereof.

FIG. 7 is a right front perspective view thereof.

FIG. 8 is a front view thereof showing cross sectional lines indicating the views in FIGS. 9-14.

FIG. 9 is a cross-sectional view thereof along line 9-9 shown in FIG. 8.

FIG. 10 is a cross-sectional view thereof along line 10-10 shown in FIG. 8.

FIG. 11 is a cross-sectional view thereof along line 11-11 shown in FIG. 8.

FIG. 12 is a cross-sectional view thereof along line 12-12 shown in FIG. 8.

FIG. 13 is a cross-sectional view thereof along line 13-13 shown in FIG. 8; and,

FIG. 14 is a cross-sectional view thereof along line 14-14 shown in FIG. 8.

The short, broken lines showing the remaining portions of the swingarm suspension plate illustrate features of the article of manufacture that form no part of the claimed design.

The broken lines consisting of dot-dash lines are boundary lines that show the claimed design extends to the boundary line, but does not include the boundary line.
